ATTORNEY.

UNITED STATES PATENT OFFICE

ALBERT B. PHISTER, OF FORT THOMAS, KENTUCKY, ASSIGNOR TO THE PHISTER MANUFACTURING COMPANY, OF CINCINNATI, OHIO, A CORPORATION OF DELAWARE

FIRE EXTINGUISHER

Application filed January 9, 1928. Serial No. 245,286.

My invention relates to fire extinguisher casings, and particularly to the heads thereof. In the past it has been customary in making fire extinguishers to provide a tubular shell, a convex sheet metal head which is soldered to the shell, and a reinforced neck which is used for a charging orifice and retainer for the cap, and which is soldered by means of an annular flange extending from the lower 10 annular edge of the neck within a central opening in the sheet head. The handles with which the extinguisher is transported or hung have been inserted and soldered in holes in the head as has been the discharge conduit. 15 The many soldered joints in holes in the thin sheet heads have been a source of weakness in the permanence of the extinguishers, because of their liability to leakage. Further, the expense required for hand labor in their manufacture has been great.

It is the object of my invention to provide a convex head formed from a metal casting which will have a neck portion integrally formed with it. Further, it is my object to 25 also cast integrally with the head a discharge portion to which a discharge conduit may be readily threaded, if desired. I further have as an object to cast integrally with the head a support extending outwardly from the periphery of the head which may be drilled for the inserting of carrying handles without it being necessary to drill through the head, thereby communicating with the interior and making a source of possible leakage. An- 30 other object is the provision of a channel in the periphery of the lower edge of the integrally cast head which will retain a flaring flange of the upper annular edge of the shell. A still further object is the provision of cast 35 lugs within the head which may be used to bend over and thereby retain a screen adjacent to the discharge orifice.

The above and other objects to which reference will be made during the ensuing dis- 45 closure I accomplish by that certain combination and arrangement of parts of which I have shown a preferred embodiment.

Referring to the drawings:—

Figure 1 is a plan view of a fire extinguisher 50 showing my novel casing structure.

Figure 2 is a vertical section taken along the lines 2—2 in Figure 1.

Figure 3 is a detail section on an enlarged scale showing the connection between the head and side walls.

Figure 4 is a detailed view of a portion 55 of the head from within showing the screen support.

Fig. 4a is an enlarged fragmentary view 60 of the cast recess for the screen.

Figure 5 is a fragmentary plan view of the extinguisher showing a modified form of supporting means.

The shell 1 forming the main body of the container is provided at its base with a spun metal bottom 2 having annular flanged portions 3 which are soldered to the interior walls of the shell. An extension 4 forms a supporting base. The head is formed with an integral casting comprising the concave disk-like portion 5 with the neck 5a integrally cast therewith.

The lower annular edge of the casting is provided with an annular groove 6a in which an annular flange 7 of the shell 1 is securely soldered. Before soldering the outer lip of the groove is turned inwardly as indicated. An inturned flange 8 extending inwardly from the base of the neck supports a cage 9 which supports a receptacle 9a which contains a chemical. The container is supplied with another chemical which, when the container is inverted, is acted on by the first chemical forming gas which generates pressure and the liquid in the extinguisher is projected through the nozzle.

The hose 10 has a coupling piece 10a into which a nipple 11 is screwed. The nipple is screwed into a threaded aperture 12 in the cast extension 13 of the head. The internal side of the head also has a recessed portion 14 integrally cast therewith with lugs 15 which are used to bend over and secure a screen 16 which prevents any sediment from being thrown onto the fire or blocking the discharge pipe.

The container 9 containing one of the reacting chemicals has a loose fitting stopper 17 which, when the extinguisher is inverted,

falls out of the neck, thereby releasing the contents.

The exterior periphery of the neck 5a is threaded as indicated at 18, and a cap member 19 is thereby secured on the neck. A flexible gasket 19a provides a seal which prevents leakage.

Extending from the outer periphery of the cap I further cast the lugs 20 which may be 10 drilled out for retaining the shanks 21 of the handle 22. In some modifications the carrying handle is not required, so that the lugs 20 may be cast as an eye, thereby providing means by which the extinguisher may 15 be supported. Such a modification is indicated in Figure 5 in which the lugs 20a form an eye 20b.

The principle of supporting a chemical container in an extinguisher with liquid 20 which will effervesce with the inversion of the container is old and well known, and I make no claim to the principle of operation of the type of extinguisher illustrated.

Having thus described my invention, what 25 I claim as new and desire to secure by Letters Patent, is:

1. In combination with a fire extinguisher casing having a tubular shell, a cast head with a neck integrally formed therewith, a 30 discharge conduit having a passage extending from the interior of the extinguisher casing in substantial alignment with the side walls of the casing and integrally formed with said head, said head further having 35 a recessed portion with lugs cast integrally with said head bent over and retaining a screen formed on the inner face of said head to filter material projected through said discharge conduit.

40 2. In combination with a fire extinguisher casing having a tubular shell, a cast head with a neck integrally formed therewith, a discharge conduit having a passage extending from the interior of the extinguisher 45 casing in substantial alignment with the side walls of the casing and integrally formed with said head, a support extending outwardly from the peripheral edge of the head also integrally cast with said head, and a recessed portion with lugs cast integrally with 50 said head bent over and retaining a screen formed on the inner face of said head to filter material projected through said discharge conduit.

55 ALBERT B. PHISTER.
